UNITED STATES PATENT OFFICE

165,937

DRAPERY TRAVERSE ROD

Harry S. Rosenbaum, Baltimore, Md., assignor to
The Eastern Venetian Blind Company, Baltimore, Md., a corporation of Maryland

Application July 11, 1951, Serial No. 15,821

Term of patent 3½ years

(Cl. D21—1)

To all whom it may concern:

Be it known that I, Harry S. Rosenbaum, a citizen of the United States, residing in the city of Baltimore and State of Maryland, have invented a new, original, and ornamental Design for a Drapery Traverse Rod, of which the following is a specification, reference being had to the accompanying drawing, forming part thereof.

Fig. 1 is a rear perspective view of the drapery traverse rod, showing my new design; and

Fig. 2 is a front perspective of the rod shown in Fig. 1.

I claim:

The ornamental design for a drapery traverse rod, as shown.

HARRY S. ROSENBAUM.
